UNITED STATES PATENT OFFICE.

JAMES THOMPSON, OF DULUTH, MINNESOTA.

FOUNTAIN-MOP.

SPECIFICATION forming part of Letters Patent No. 727,863, dated May 12, 1903.

Application filed June 26, 1902. Serial No. 113,236. (No model.)

To all whom it may concern:

Be it known that I, JAMES THOMPSON, a citizen of the United States, residing at Duluth, in the county of St. Louis and State of Minnesota, have invented certain new and useful Improvements in Fountain-Mops; and I do hereby declare the following to be a full, clear, and exact description of the invention, such as will enable others skilled in the art to which it appertains to make and use the same.

My invention relates to fountain-mops, and has for its object the provision of a mop-head containing a reservoir for liquid, from which the liquid is adapted to flow through valve-controlled ports onto and seep through a cloth clamped to said mop-head.

With this and other objects in view it consists of a mop-head containing a reservoir formed with outlet-ports, a slide-valve for controlling said ports, means for operating said valve, means for locking said operating means, handle-attaching means, a cover for said reservoir, a handle for operating said mop, mop-cloths, and clamping means for securing said cloths to said mop-head.

It also consists of certain other constructions, combinations, and arrangements of parts, as will be hereinafter more particularly described and claimed.

In the drawings, Figure 1 is a transverse section, partly in elevation, through said mop-head and handle. Fig. 2 is a longitudinal section through said mop-head. Fig. 3 is a rear elevation of said mop-head, and Fig. 4 is a front elevation of said mop-head.

In the drawings, 1 is the front half of the mop-head, of which 2 is the rear half, which halves are each partly hollowed out to form a reservoir when said halves are secured together, as they normally are, by the rod 3 and screws 4 and any additional suitable means. (Not shown.) The opposite ends of said rod 3 are bent at right angles to the central portion of said rod and are projected through said halves 1 and 2 and through the corresponding ends of a clamp-bar 5, which is secured on said rod by thumb-nuts 6. The part 1 is provided with a plural number of outlet-ports 7, communicating with said reservoir, which ports are adapted to be wholly or partly covered by a slide-valve 8, seated in a channel formed in the bottom of the reser-

voir portion of said part 1, and which valve is provided with a number of apertures 9 corresponding to the number of said ports 55 and with upwardly-extending lugs 10, between which lugs extends the foot of a vertically-arranged arm 11, secured to one end of a horizontally-arranged shaft 12, extending through the front wall of said part 1 and carrying upon its outer end an index-lever 13, projected through a guide 14, to which it is adapted to be locked by a set-screw 15, extending through a slot in said guide and adapted to draw said lever into frictional relation 65 with said guide. Upon the outer face of part 2 is secured in any suitable manner a plate having sockets 16 and 17 at different angles formed thereon, each of which is respectively adapted at various times to receive the end of 70 an operating-handle 18. Said reservoir is provided with a suitable cover, as 19, hinged, as at 20, to said part 2 or in any suitable manner to either part 1 or 2, which cover is adapted to be secured by a hook 22, secured 75 to said part 1 and projected into a screw-eye 21, fixed in the edge of said cover. A scale 20 is marked on said part 1, with which scale the index-lever 13 is adapted to register, and which scale determines the position of the 80 valve with regard to said ports. It is obvious, however, that said cover may within the scope of my said invention be formed, hinged, and locked in a variety of ways and that said construction is within the scope of said invention capable of minor modifications, and I do not, therefore, desire to limit myself to the exact means shown.

In operation one edge of the cloth is inserted from the top between the rod 3 and the 90 front face of said part 1, the cloths being carried over said rod and downward and closely under the lower edges of said united parts 1 and 2, beneath said ports, and upward between the face of part 2 and the opposing face 95 of said bar 5. The nuts 6 are then turned to draw the ends of said rod 3 farther through said bar 6, thereby clamping one edge of said cloth tightly between said rod and the front face of said mop-head and clamping the other 100 longitudinal edge of said cloth tightly between said bar and the rear face of said head. If desired, the ends of the cloth may be prolonged beyond the ends of the mop-head and

gathered up in any suitable manner over the lower portion of the ends of the mop-head and sewed to contiguous clamped parts of the cloth, so as to retain its position. The index-
5 lever is then directed to the mark on said scale indicating that said ports are closed, the moving of said arm turning said shaft 12 and moving said arm 11, thereby operating said valve 8 to close said ports. The reser-
10 voir is then filled with oil or other liquid to be applied and the cover closed. The lever 13 is then directed to a point on the said index indicating that the ports are opened to a desired extent, and said lever is then
15 clamped in position by said thumb-screw. The oil, paint, or other liquid then seeps through said cloth and is applied to the surface to be operated upon by operating the mop in the usual manner. The variously-di-
20 rected sockets 16 and 17 adapt the mop for use upon surfaces in various planes.

Having now described my invention, what I claim, and desire to secure by Letters Patent, is—

25 1. In a fountain-mop, a mop-head embodying a reservoir provided with downwardly-di-
rected outlet-ports, a slide-valve adapted to govern said ports in such manner as to si-
multaneously open or close all of the same,
30 means for operating said valve, indicating means for disclosing the degree in which said ports are uncovered by said valve, means for securing said valve in a predetermined position, substantially as described.

35 2. In a fountain-mop, a mop-head comprising a body portion formed of two parallel parts vertically arranged in the same horizontal plane with respect to each other, and respectively having a recess, open at the top
40 formed in their relatively opposing broad faces and adapted to register with each other

and in coöperation with each other to form a reservoir, said parts being transversely aper-
tured near each end for the passage of clamp-
ing means; clamping means for securing said 45 parts together comprising a rod having its ends threaded and bent at right angles to its central portion and adapted to be projected through said apertures from one side of said head, a bar, apertured at each end and 50 mounted on the projecting ends of said rod upon the opposite side of said head from the central portion of said rod, and nuts screwed upon the ends of the respective angular pro-
jections of said rod, said clamping means be- 55 ing also adapted to clamp the opposite longitudinal edges of mop-cloths to said mop-head substantially as described.

3. In a fountain-mop, the combination of a 60 mop-head having a body portion formed of two recessed parts adapted when clamped together to form a reservoir, provided with downwardly-directed outlet-ports, governed by a slide-valve arranged within said reservoir, means for operating said valve, means 65 for locking said operating means in a prede-
termined position, distributing means adapt-
ed to govern the outflow from said reservoir at the mouths of said ports and comprising a cloth, or cloths clamped to said body portion 70 on each side thereof and extending under said ports, clamping means adapted to secure said cloths to said body portion and to secure the parts of said body portion together, substan-
tially as described. 75

In testimony whereof I hereunto affix my signature in presence of two witnesses.

JAMES THOMPSON.
